United States Patent Office.

A. W. BALL, OF DELAWARE GROVE, PENNSYLVANIA.

Letters Patent No. 90,980, dated June 8, 1869.

IMPROVEMENT IN HARROWS.

The Schedule referred to in these Letters Patent and making part of the same.

To all whom it may concern:

Be it known that I, A. W. BALL, of Delaware Grove, in the county of Mercer, and State of Pennsylvania, have invented a new and improved Harrow; and I do hereby declare that the following is a full, clear, and exact description thereof, which will enable others skilled in the art to make and use the same, reference being had to the accompanying drawings, forming part of this specification.

This invention relates to a new and improved harrow, and it consists in a novel construction of the same, as hereinafter fully shown and described, whereby several advantages are obtained, as hereinafter set forth.

In the accompanying sheet of drawings—

Figure 1 is a plan or top view of my invention constructed of wood.

Figure 2, a rear view of the same.

Figure 3, a plan or top view of my invention constructed of metal.

Figure 4, a plan or top view of a portion of a harrow, showing a modification of my invention.

Similar letters of reference indicate corresponding parts.

My improved harrow is constructed of two equal parts, A A, (see figs. 1 and 2,) connected by joints to a central rod, B.

Each part, A, is composed of three bars, *a b c*, the bars *a b* being parallel with each other, and connected at their rear ends to the bar *c*.

The bars *a b* are connected by a cross-bar, *d*.

The bars *a b* have sockets *e* attached to them by bolts *f*, and in these sockets the harrow-teeth *g* are fitted.

The inner ends of the bars *a b c* are provided with eyes *h*, through which the rod B passes.

By this arrangement each part, A, of the harrow is allowed to rise and fall freely, and conform to the inequalities of the surface of the ground over which they may pass.

The invention is not confined to the use of wood as a material.

In fig. 2 an iron-frame harrow is shown, constructed substantially in the same way.

The bars *a b* may, in this case, be made out of one piece, but in proper form, or they may be made of separate pieces.

The sockets *e* may be of wrought or cast-iron attached by bolts as shown in fig. 2, or they may be made out of a wrought-iron bar, *h*, bent or swaged to form the sockets, as shown in fig. 4, said bar, *h*, being secured by bolts to the bar *a* or *b*.

This harrow is extremely simple in construction, and may be manufactured at a very moderate cost, either of wood or iron.

I prefer the iron harrow, however, as it is more durable, not liable to choke or clog, and it is a better or more efficient pulverizer.

I do not confine myself to any precise position of the inner bars *b*, for they may be placed parallel with the bars *a*, as shown in fig. 2, and bolted to the bars *a c*.

The team is attached to the front end of the central rod B.

Having thus described my invention,

What I claim as new, and desire to secure by Letters Patent, is—

The metallic harrow, constructed as described, of two parts, A A, each composed of bars, *a c*, strengthened by the brace *b*, and hinged to the central bar B, in such a manner as to operate independently of each other, the bars *a b* being provided with the metallic sockets *e*, for the teeth *g*, all arranged as described for the purpose specified.

A. W. BALL.
